NATHAN K. GARHART, OF WATERTOWN, MASSACHUSETTS, ASSIGNOR TO GARHART DENTAL SPECIALTY CO., OF SOMERVILLE MASSACHUSETTS, A CORPORATION OF MASSACHUSETTS

BOTTLE

Application filed October 3, 1927. Serial No. 223,520.

The invention to be hereinafter described relates to bottles for dispensing materials, such, for example, as cement and a phosphoric acid preparation used by dentists.

Heretofore, for this purpose a bottle has been provided having a dispensing stopper comprising a plug having a hole extending therethrough and a glass tube fitted into the hole and projecting a substantial distance out beyond the plug. The tube has a tapered delivery end and is provided with a removable cap. The construction is such that on removal of the cap, the bottle may be grasped and shaken, thereby to discharge liquid from the bottle drop-by-drop.

It has been found that frequently the glass tube becomes loosened in the hole in the plug and is liable to be pulled therefrom when attempting to draw the cap off from the tube. One of the purposes of the present invention is to overcome this difficulty. To accomplish this, an elastic rubber plug is provided having a hole extending therethrough, and formed integral with the plug is an elastic rubber tube projecting from the plug. The construction is such that in the use of the bottle there is no danger of the tube escaping from the plug.

The tube is provided with a removable cap which is so formed that it slightly compresses the elastic tube when slid thereon. The tendency of the compressed tube to expand insures tight leak preventing engagement between the cap and tube for a long time.

With the aforesaid and other purposes in view, the character of the invention may be best understood by reference to the following description of one good form thereof shown in the accompanying drawing, wherein:

Fig. 1 is a vertical section through the bottle;

Fig. 2 shows perspective views of the plug with its tube, the stiffening quill and the cap;

Fig. 3 is a view looking toward the top of the bottle; and

Fig. 4 is a vertical section through the upper part of the bottle and through the

stopper showing compression of the tube on application of the cap thereto.

Referring to the drawing, the bottle shown therein as one good form of the invention, preferably is made of glass and comprises a body 1 having a wide neck 3 with an outer threaded portion 5 above a circumferential bead 7.

The dispensing stopper for the bottle comprises a plug 9 made of high grade elastic rubber. Projecting from the upper end of the plug is a flange 11 serving as a gasket for engagement with the rim of the neck. Preferably the inner wall 13 of the neck is tapered somewhat so that when the plug is forced into the neck, it will be compressed and tend to expand into tight wedging engagement with said wall.

The plug has a hole 15 extending therethrough at the center thereof. Projecting from the plug and molded or formed integral therewith is an elastic rubber tube 17 in registration with the hole in the plug. The outer end of the tube is tapered and has a small delivery hole therein.

Preferably means is provided for stiffening the tube. To accomplish this, in the present instance, a quill 19 of celluloid or other suitable material is inserted through the plug up substantially to the tapered end of the tube, and the quill may be secured in the plug and tube by shellac varnish or other suitable adhesive. The shellac varnish is desirable, since it is not dissolved or affected by phosphoric acid.

The cup-shaped cover 21 of celluloid or other suitable material fits over the plug and the upper end of the neck, and has a threaded portion 23 adapted to be screwed onto the neck to hold the plug in the neck and press the gasket against the rim of the neck. The cover has a central aperture 25 through which the tube extends and made somewhat larger than the outside diameter of the tube. The top of the cover is domed so as to leave a recess 27 between the top and the upper end of the plug.

A thimble-shaped cap 29 of rubber or other suitable material is formed to fit onto the rubber tube and when slid thereon slightly com-

press the same, as will be noted in Fig. 4. The inherent resilience of the tube will cause it to tend to expand and maintain tight engagement with the cap. The lower end of the cap has a bead or flange 31 for engagement with the cover and is sufficiently wide to cover the space between the tube and the cover aperture.

The plug is made shorter than the bottle neck in order to leave an air space 33 above the liquid filling the body of the bottle, which will allow expansion of the liquid without danger of starting the plug from the neck. It is desirable that the bottle neck and the stopper shall be of considerable width, in order that there may be a body of rubber sufficiently large to yield or bulge upward somewhat on expansion of the liquid in the bottle without withdrawing the plug from tight engagement with the neck. The quill has sufficient stiffness to properly support the rubber tube, but is capable of a certain amount of flexion, and therefore will not materially interfere with the yielding and bulging of the plug.

In use, when it is desired to dispense the liquid from the bottle, the cap is removed from the tube, and the bottle is firmly grasped and shaken to cause the liquid to discharge from the end of the tube drop-by-drop.

The dispensing stopper having the elastic rubber tube projecting from and formed integral with the plug, is a very desirable feature, since there is never danger of removal of the tube from the plug and no chance of leakage of liquid between the plug and tube. By forming the plug and tube of high grade elastic rubber, tight fit of the plug in the neck and tight fit of the cap on the tube are insured. It is desirable to form the cap of elastic rubber, since it is found that the rubber cap will have intimate engagement with the rubber tube on the plug and permanently prevent leakage of the liquid from the tube and out between the tube and cap.

The features of the bottle and stopper described above combine to produce an article which is simple and cheap in construction and highly satisfactory for the requirements and conditions of its use.

It will be understood that the invention is not limited to the specific embodiment shown, and that various deviations may be made therefrom without departing from the spirit and scope of the appended claims.

What is claimed is:

1. The combination of a bottle and a dispensing stopper therefor comprising an elastic rubber plug fitting into the neck of the bottle and having a hole therein, an elastic rubber tube projecting from the plug in communication with said hole, a stiffening quill in the tube, and a cap on the tube.

2. The combination of a bottle and a dispensing stopper therein comprising an elas-

tic rubber plug fitting into the neck of the bottle and having a hole extending therethrough, an elastic rubber tube projecting from the plug and communicating with said hole, a stiffening quill in the tube, and a thimble-shaped cap fitted onto the tube and adapted to compress the same somewhat to maintain tight engagement therewith.

3. The combination of a bottle and a dispensing stopper therefor comprising an elastic rubber plug having a hole extending therethrough, an elastic rubber tube projecting from and integral with the plug and communicating with said hole, a stiffening quill secured in the tube, a flange projecting from the plug over the rim of the neck, a cover having an aperture receiving the tube and threaded to the neck, and a cap for the tube having an end adapted to engage the cover, said cap being formed to compress the tube somewhat, thereby to insure tight engagement therewith.

4. The combination of a bottle having a body and a neck tapered inward upward toward the end of the neck, and a dispensing stopper comprising an elastic rubber plug expansible into close engagement with the tapered neck and having a hole extending through the plug, an elastic rubber tube extending from and integral with the plug and communicating with the hole in the plug, and a removable cap on the tube.
